UNITED STATES PATENT OFFICE.

WESLEY W. HODGSON, OF AILSA CRAIG, ONTARIO, CANADA.

AUTOMATIC STARTER FOR INTERNAL-COMBUSTION ENGINES.

1,104,894.

Specification of Letters Patent. Patented July 28, 1914.

Application filed April 24, 1914. Serial No. 834,104.

To all whom it may concern:

Be it known that I, WESLEY W. HODGSON, a subject of the King of Great Britain, residing at Rural Route No. 2, Ailsa Craig, 5 county of Middlesex, Province of Ontario, Canada, have invented certain new and useful Improvements in Automatic Starters for Internal-Combustion Engines, of which the following is a specification.

10 My invention relates to improvements in automatic starters for internal combustion engines and the principal objects of my invention are, firstly, to provide a spring-operated starter for internal combustion engines which will do away with cranking, and automatically operate the engine at a uniform speed until it generates its own power, at the same time performing the function of a fly wheel for the engine; secondly, to so construct my starter that the motor thereof may be supplied with energy from the engine when the engine is in operation, thus avoiding the necessity of having to apply any outside power to store energy 20 in said starter; thirdly, to provide a particular form of winding brake so that the starter may be wound up without danger of holding part of the same from rotation after the winding of the spring thereof and so prevent any possibility of the engine being stopped by the brake; fourthly, to provide a particular construction of ratchet plate designed to be carried by the frame of the engine, in order that the said plate may 30 be readily removed without the necessity of removing the starter from the engine shaft, in order to effect repairs or make adjustments, and the construction of my invention will be hereinafter set forth and what I 40 claim as new will be pointed out in the appended claims.

Figure 1 is a side elevation of my starter, looking at the inner side thereof, the engine shaft being shown in section and certain 45 parts being broken away to illustrate internal construction. Fig. 2 is a side elevation of my engine starter looking at the outer side thereof. Fig. 3 is a vertical cross section on the line 3-3 Fig. 1 on an enlarged scale. Fig. 4 is a vertical cross section on the line 50 4-4 Fig. 1, and Fig. 5 is a perspective view of a sleeve hereinafter referred to.

In the drawings, like characters of reference indicate corresponding parts in each 55 figure.

Several advantages accrue from the use of my engine starter. One of these advantages is that there will be no necessity of utilizing electrical energy developed by batteries, as is now commonly done, in order to get ignition 60 sparks from the magneto, since my starter generates sufficient speed in the engine in order to cause the magneto to operate. The facts set forth will permit of much saving 65 in the cost of operating an internal combustion engine.

A is the engine shaft, and the same is mounted in suitable bearings B carried by the engine frame C.

D is a disk wheel provided with a hub E 70 mounted on the shaft A and secured thereto by any suitable means such as the key F. Carried by the disk wheel D and mainly projecting beyond the inner side thereof, are a plurality of centrifugal governors preferably constructed as follows:

G are rods radially positioned in respect to the engine shaft A, and these rods are mounted in suitable bearings H carried by the disk wheel D. The said rods are held in 80 said bearings by cap plates I of any suitable construction secured in position by the screws J. The upper ends of the rods G are threaded, and screw into the threaded holes K formed in the governor weights L. Each 85 rod G is provided with a nut M screwing thereon which locks the said rods in adjusted position.

N are adjusting lugs fixed to the rods G and whereby the same are adjusted. 90

As illustrated particularly in Fig. 3, the governor weights L overhang the disk wheel D. The periphery of the said disk wheel D is removed where the governor weights L are positioned so as to form openings O. 95 This construction permits said governor weights to be positioned within the periphery of the said disk wheel D, in order to provide compactness in construction. Pivot-ed on studs P projecting beyond the inner 100 side of the disk wheel D are a plurality of brakes Q. The said brakes are positioned at the mouths of the openings O and over-hang the periphery of the disk wheel D for the greater portion of their length. Split 105 pins P held by the studs P retain the brakes Q in place. Secured to the inner side of each brake Q and near the outer end thereof, is a leaf spring 2. The said leaf springs are each positioned against the inner side of a 110

pin or bolt 3 projecting beyond the inner side of the disk wheel D, and they are held in tension by means of the adjusting screws 4 which screw through the threaded lugs 5 also carried by the disk wheel D. By means of the adjusting screws 4 the tension of the leaf springs 2 can be regulated. The said leaf springs normally rest in contact with the governor weights L and retain them in normal position. Each governor weight is integrally provided with a shank 6 which extends through a longitudinal slot 7 formed in each of the lugs 8 which preferably form part of the disk wheel D.

15 9 is a link pivoted by the pin or rivet 10 to each shank 6. Each link 9 is in turn pivoted by the pin or rivet 11 to the disk wheel D. Suitable play is allowed the rods G in their bearings H so that the governor weights L may be free to move radially outwardly and inwardly without interference from the links 9. The object of the links pivoted to the governor weights L is to relieve the rods G substantially of all lateral strain which at times is brought into play through the inertia of the governor weights L.

12 is a disk wheel provided with a hub 13 loosely mounted on the engine shaft A. 30 The disk wheel 12 is provided with a friction rim 14 which overhangs the disk wheel D and the governing means already described.

15 is a disk wheel provided with a hub 16 which is loosely mounted on the engine shaft A. The inner ends of the hubs 13 and 16 touch, and as they are of the same diameter, I am enabled to mount thereover a sleeve 17 which extends between the disk wheels 12 and 15. The sleeve 17 is fastened by the key 18 or equivalent means to the hub 13.

The disk wheel 15 is provided with a flange or rim 19 which projects beyond the inner side of said disk wheel and preferably overhangs portion of the disk wheel 12. The construction already described provides a closed chamber 20 between the disk wheels 12 and 15, and positioned within this chamber is a coiled spring 21 of the required strength, which surrounds the sleeve 17. The inner end of this spring is fastened by any suitable means to the sleeve 17, and the outer end of this spring is fastened by any suitable means to the flange or rim 19.

55 22 is a toothed disk wheel mounted on the engine shaft A adjacent the outer side of the disk wheel 15, and keyed to the said shaft by the key 23, or equivalent means.

Feathered on the hub E by means of the feather key 24 is a sleeve 25. Suitably carried by the engine frame C is a circular ratchet plate 26 provided with a central opening 27 surrounding the shaft A. Passing through a hole 28 shown dotted in Fig. 35 3, is a lever 29. This lever is pivoted by the

pin or bolt 30 between the lugs 31 carried by the inner side of the ratchet plate 26 and shown particularly by dotted lines in Fig. 1. The inner end of the lever 29 is bifurcated as shown at 32, and the extremities 33 of the said bifurcated end rest in the annular groove 34 formed between the flanges 35 carried by the sleeve 25. The construction of lever 29 and sleeve already described is of course well known, and it will be understood that any type of lever adaptable for use in connection with my starter may be used by me.

As before set forth, the ratchet plate 27 is preferably carried by the engine frame. I construct the said ratchet plate of two parts 26^a and 26^b. These said parts are secured to the engine frame C by any suitable means such as the threaded bolts 36 tapped into the engine frame. The said circular plate 26 is of course stationary and is merely used as means to co-act with the dogs 37 (which are pivoted by the pins 38 to the friction rim 14) to prevent the backward movement of the disk wheel 12. These dogs 39 engage with the teeth a of the ratchet plate 26 at certain times for the purpose stated. When the starter attains full speed, the said dogs 27 are thrown by centrifugal force outward against the stop pins 93 carried by the friction rim 14, and are retained in this position by the speed out of contact with the teeth a, thus preventing any noise from these parts when the engine is at work.

In order to effect repairs, or to make adjustments to the governing means already described, all that is necessary is to remove the threaded bolts 36 securing the part 26^a of the ratchet plate 26 to the engine frame, and remove this part. Since the part 26^b of the plate 26 is stationary, an opening is formed in the said plate 26 of the required width which will permit the part 26^a to be pulled over the shaft thus exposing the governing means. This construction obviates any necessity of having to remove the starter from the engine shaft A for the purpose mentioned. The parts 26^a and 26^b of course fit more or less snugly at their opposing edges b, and when the part 26^a is replaced the toothed perimeter of the plate 26 will be complete. One or more openings c may be made in the ratchet plate 26 to permit of access to the governing means and so obviate the necessity of always having to remove the part 26^a. The sleeve 25 is provided with a plurality of extensions 43 which are beveled at their outer sides. The extensions 43 correspond in number to the rods G, and the function performed by these extensions is to come in contact with the inner ends i of the rods G when the sleeve 25 is moved along the hub E in the direction indicated by arrow. The contact of the ex-

tensions 43 with the rods G will force these rods outwardly and through the medium of the governing weights L, force the shoes i of the brakes Q into contact with the inner surfaces of the friction rim 14. The annular surface 1 of the sleeve 25 will be supporting the inner ends i of the rods G when the shoes i are in contact with the friction rim 14. When the parts are in the position just described, the disk wheel 12, which is loosely mounted on the shaft A, is clutched to the shaft. The disk wheel D is provided with a plurality of holes n in the path of movement of the extensions 43. These holes n of course may be omitted when the rods G are placed farther away from the disk wheel D than illustrated.

Having described the principal parts of my invention, I shall now describe its operation. For the purpose of this description, it is assumed that the spring 21 is wound up tight. The function of the dogs 37 is to prevent the disk wheel 12 being rotated in the direction opposite to the direction of movement of the engine shaft A. The coiled spring 21, after the brake hereinafter described is thrown out of contact with the flange or rim 19, exerts energy and rotates the disk wheel 15 in the direction indicated by arrow in Fig. 2.

40 are a plurality of dogs pivoted by pins 41 to the outer side of the disk wheel 15. These dogs are in engagement with the teeth 42 of the disk wheel 22, and it is through their medium that energy is transmitted from the disk wheel 15 through the disk wheel 22 to the engine shaft A.

Previous to the operation just described, it must be understood that the lever 29 has been operated to move the sleeve 25 toward the engine frame to move the extensions 43 out of the path of movement of the rods G, to allow the springs 2 to move the brakes Q away from contact with the friction wheel 14 and to return the governing weights L back to normal position. This leaves the governing weights L free to move outwardly under centrifugal force so as to insure the engine shaft being revolved at a uniform speed. So soon as the engine develops its own power, the governor weights L are moved farther outwardly causing the brakes Q to be jammed against the friction rim 14, resulting in the clutching of the disk wheel 12 to the engine shaft.

With the exception of the ratchet plate 26 and lever 29, the parts described rotate with the engine shaft, and consequently the starter performs the function of a balance wheel. When the whole 55 starter is revolving with the engine shaft, the lever 29 is operated to position the extensions 43 underneath the inner ends i of the rods G so as to positively hold the brakes Q in contact with the friction roller 14 in order that the disk wheel 12 will be positively

clutched to the shaft A and be bound to rotate with the other parts. The dogs 40 are constructed with weighted tails d so that under the influence of centrifugal force, the said dogs will always be held in engagement with the teeth 42.

As before set forth, I utilize the energy developed by the engine to wind the motor or coiled spring 21. Pivoted by the pin 44 to a suitable support 45, is a lever 46 to the outer end of which is pivoted a brake shoe 47 by a pin 48.

49 is a lever pivoted on the pin 44, and this lever operates between the stops 50 and 51 carried by any suitable support.

52 is an extension carried by the lever 49 which overlaps the lever 46 near its upper portion. When the starter is exerting energy to start the engine, the spring 53, coupling the lever 49 with the stop 51, keeps 85 the lever 49 in contact with the stop 51, with the result that through the extension 52 the lever 46 is moved to keep the brake shoe 47 out of contact with the flange or rim 19. In order to wind the spring 21, it is necessary that the disk wheel 15 be held stationary. In order to hold this disk wheel stationary, the lever 49 is moved into contact with the stop 50, and through the medium of the spring 54, (suitably positioned 90

between this lever and the upper end of the lever 46, and held in place by any suitable construction well known in machine practice,) pressure is exerted against the lever 46 which causes the brake shoe 47 to be 100 moved and held in contact with the flange or rim 19. This brake shoe will prevent the rotation of the disk wheel 15 with the result that the spring will be wound up. The dogs 40 will of course co-act with the teeth 42 of the disk wheel 22 to prevent the unwinding of the spring. When the spring is wound up, the lever 49 is released when it immediately returns to normal position through the medium of the spring 53 and releases the 110 brake shoe 47.

The spring 54, or equivalent means, is very important. The strength of this spring is just sufficient to permit the shoe 47 to have sufficient friction against the flange or rim 115 19 to hold the disk wheel 15 at rest only until the spring 21 has been wound up. Should the operator hold the lever 49 against the stop 50 too long, notwithstanding the fact that the shoe 47 may be in contact with the flange or rim 19, it can not prevent the rotation of this rim with the engine shaft after the said spring has been wound up. The object of this is to prevent the levers 49 and 46 being a means whereby 120 the engine is brought to rest through oversight on the part of a careless operator.

From the foregoing specification it is clear that my starter will enable the engine to develop its own power without the necessity of 125

cranking. Of course the starter can be adapted to be used in connection with any type of internal combustion engine, whether for stationary or mobile use.

5 Since my starter performs the function of a fly wheel, it does not take up any extra space.

Any suitable type of levers already described may be employed, and the same may 10 be positioned as the requirements of installation may demand.

While I have described what I consider to be the best embodiment of my invention, I desire it to be understood that the principle 15 can be embodied in different forms and I desire not to be limited beyond the requirements of the prior art and the terms of my claims.

When the spring 21 is exerting energy to 20 rotate the engine shaft A, it naturally follows that the disk wheel 12, being loosely mounted on the shaft A, is stationary, and it is held at rest by reason of the dogs 37 thereof engaging with the teeth a.

25 What I claim as my invention is:

1. The combination with an engine shaft, of an automatic starter therefor comprising a first disk wheel keyed to said shaft; a second disk wheel loosely mounted on said 30 shaft and provided with a friction rim; a third disk wheel loosely mounted on said shaft and provided with a flange or rim; a coiled spring surrounding said shaft and having its inner end secured to said second 35 mentioned disk wheel and its outer end secured to said third mentioned disk wheel; means co-acting with said third mentioned wheel whereby when this disk wheel is rotated by said spring, the rotary motion 40 thereof will be transmitted to said engine shaft; governing means carried by said starter to be centrifugally moved to clutch said second mentioned disk wheel to said engine shaft through the medium of its friction rim; means whereby said governing 45 means may be manually thrown into action, and means to prevent the rotation of said second-mentioned disk wheel in a direction opposite to the direction of rotation of said 50 engine shaft when said governing means is not clutching said second-mentioned disk wheel to said engine shaft.

2. The combination with an engine shaft, of an automatic starter therefor comprising 55 a first disk wheel keyed to said shaft; a second disk wheel loosely mounted on said shaft and provided with a flange or rim; a third disk wheel loosely mounted on said shaft and provided with a flange or rim; a 60 coiled spring surrounding said shaft and having its inner end secured to said second mentioned disk wheel and its outer end secured to said third mentioned disk wheel; means co-acting with said third mentioned 65 disk wheel whereby when this disk wheel is

rotated by said spring, the rotary motion thereof will be transmitted to said engine shaft; governing means comprising a plurality of rods radially mounted in respect of said engine shaft; bearing members carried by said first-mentioned disk wheel in which said rods are mounted; governor weights carried by the outer ends of said rods and positioned underneath the friction rim of said first-mentioned disk wheel; 70 brakes pivoted to said first-mentioned disk wheel and positioned intermediate said friction rim and said governor weights; means whereby said brakes and governor weights and the rods thereof are held in normal position; a sleeve mounted to move longitudinally on said engine shaft and to rotate therewith, and designed to be operated to force said governor weights and brakes outward through the medium of said rods to 75 clutch said second-mentioned disk wheel to said shaft; lever mechanism for moving said sleeve, and means whereby said second-mentioned disk wheel is held from rotating in a direction opposite to the direction of rotation of said shaft. 80

3. The combination with an engine shaft, of an automatic starter therefor comprising a first disk wheel provided with a hub keyed to said engine shaft; a second disk wheel 95 provided with a hub loosely mounted on said engine shaft, and further provided with a friction rim which overhangs said first-mentioned disk wheel; a third disk wheel provided with a hub loosely mounted on said 100 shaft, and further provided with a flange or rim which overhangs the said hubs of said loosely mounted disk wheels; a sleeve mounted over the hubs of said last mentioned disk wheels and fixed to the hub of said second-mentioned disk wheel; a coiled spring positioned between said loosely mounted disk wheels and surrounding said 105 shaft and having its inner end secured to said sleeve and its outer end secured to said flange or rim; a toothed disk wheel fixed to the outer end of said shaft; a plurality of weighted dogs pivoted to said third-mentioned disk wheel and designed to coact with said toothed disk wheel; a plurality of 110 brakes pivoted to said first-mentioned disk wheel and operating underneath said friction rim; springs whereby said brakes are held in normal position; a plurality of governing means radially mounted in respect 115 of said shaft and carried by said first-mentioned disk wheel and in the path of movement of said brakes by means of which they are held in normal position; a sleeve feathered on the hub of the said first-mentioned disk wheel and designed to move said governing means radially outward at certain times to force said brakes into frictional contact with said friction rim; lever mechanism for moving said sleeve, and means 120

whereby said second-mentioned disk wheel is prevented from rotating in a contrary direction to the engine shaft.

4. The combination with an engine shaft, 5 and the engine frame, of an automatic starter therefor comprising a first disk wheel provided with a hub keyed to said engine shaft; a second disk wheel provided with a hub loosely mounted on said engine shaft, and further provided with a friction 10 rim which overhangs said first-mentioned disk wheel; a third disk wheel provided with a hub loosely mounted on said shaft, and further provided with a flange or rim 15 which overhangs the said hubs of said loosely mounted disk wheels; a sleeve mounted over the hubs of said last-mentioned disk wheels and fixed to the hub of said second-mentioned disk wheel; a coiled 20 spring positioned between said loosely mounted disk wheels and surrounding said shaft and having its inner end secured to said sleeve and its outer end secured to said flange or rim; a toothed disk wheel fixed 25 to the outer end of said shaft; a plurality of weighted dogs pivoted to said third-mentioned disk wheel and designed to co-act with said toothed disk wheel; a plurality of brakes pivoted to said first-mentioned disk 30 wheel and operating underneath said friction rim; springs whereby said brakes are held in normal position; a plurality of governing means radially mounted in respect of said shaft and carried by said first-mentioned disk wheel and in the path of movement of said brakes by means of which they are held in normal position; a sleeve feathered on the hub of the said first-mentioned disk wheel and designed to move said governing means radially outward at certain 35 times to force said brakes into frictional contact with said friction rim; a circular ratchet plate provided with a central opening through which said engine shaft passes, 40 and composed of two parts suitably bolted to said engine frame in such a manner as to permit one of said parts to be removed; dogs pivoted to the friction rim of said first-mentioned disk wheel and designed to co-act at 45 certain time with the teeth of said ratchet plate, and a lever passing through a hole formed in said ratchet plate and having its inner end positioned to co-act with said sleeve to move it longitudinally on said shaft, and 50 means whereby said lever is pivoted to said ratchet plate.
5. The combination with an engine shaft, 55 of an automatic starter therefor comprising a first disk wheel keyed to said shaft; a second disk wheel loosely mounted on said shaft and provided with a flange or rim; a third disk wheel loosely mounted on said shaft and provided with a flange or rim; a coiled spring surrounding said shaft and 60 having its inner end secured to said second

mentioned disk wheel and its outer end secured to said third mentioned disk wheel; means co-acting with said third mentioned disk wheel whereby when this disk wheel is rotated by said spring, the rotary motion 70 thereof will be transmitted to said engine shaft; governing means comprising a plurality of rods radially mounted in respect of said engine shaft; bearing members carried by said first-mentioned disk wheel in 75 which said rods are mounted; governor weights carried by the outer ends of said rods and positioned underneath the friction rim of said first-mentioned disk wheel; brakes pivoted to said first-mentioned disk 80 wheel and positioned intermediate said friction rim and said governor weights; means whereby said brakes and governor weights and the rods thereof are held in normal position; a sleeve mounted to move longitudinally on said engine shaft and to rotate therewith and designed to be operated to force said governor weights and brakes outward through the medium of said rods to clutch said second-mentioned disk wheel 85 to said shaft; lever mechanism for moving said sleeve; means whereby said second-mentioned disk wheel is held from rotating in a direction opposite to the direction of rotation of said shaft; a pair of levers pivoted to a support, one of said levers being provided with a brake shoe designed at times to brake against said third mentioned disk wheel to hold it from rotation, and a spring mounted between said levers and whereby 90 energy is transmitted from the operation lever to said shoe-provided lever and which prevents the operator applying sufficient energy to stop the engine after the spring has been wound up.

6. The combination with an engine shaft, of an automatic starter therefor comprising a first disk wheel keyed to said shaft; a second disk wheel loosely mounted on said shaft and provided with a friction rim 110 which overhangs said first-mentioned disk wheel; a third disk wheel loosely mounted on said shaft and provided with a flange or rim, a coiled spring surrounding said shaft and having its inner end secured to said second-mentioned disk wheel and its outer end secured to said third-mentioned disk wheel; means co-acting with said third mentioned disk wheel whereby when this disk wheel is rotated by said spring the rotary motion 115 thereof will be transmitted to said engine shaft; governing means comprising a plurality of rods radially mounted in respect of said engine shaft; bearing members carried by said first-mentioned disk wheel in 120 which said rods are mounted; governor weights carried by the outer ends of said rods, each weight being provided with a shank which operates through a longitudinal slot formed in lugs carried by said first- 125

mentioned disk wheel; a link pivoted to each of the said lugs and pivoted to said first-mentioned disk wheel; brakes pivoted to said first-mentioned disk wheel and positioned intermediate said governor weights; leaf springs whereby said brakes and governor weights and the rods therefor are held in normal position; a sleeve mounted to move longitudinally on said engine shaft and to rotate therewith, and designed to be operated to force said governor weights and brakes outward through the medium of said

rods to clutch said second-mentioned disk wheel to said shaft; lever mechanism for moving said sleeve, and means whereby said second-mentioned disk wheel is held from rotating in a direction opposite to the direction of rotation of said shaft. 15

In testimony whereof I have affixed my signature in presence of two witnesses.

WESLEY W. HODGSON.
